[57] ABSTRACT

[21] Appl. No.: 132,111

A rifle bolt action having a cocking piece secured to a firing pin assembly carried within the bolt. A cam on the cocking piece rides on a cam surface of the bolt, so that the cocking piece cocks the firing pin when the bolt is rotated. The cocking piece is housed within a cover to prevent rotation of the cocking piece when the bolt is rotated. Cooperating surfaces of the cocking piece, the cover and receiver of the rifle bolt action prevent torque or stress from being exerted on the firing pin assembly when it is cocked.

BOLT ACTION RIFLE COCKING PIECE AND COVER THEREFOR

This invention relates to firearms and more particularly to a cocking piece and cocking piece cover arrangement for a bolt action rifle.

Many factors must be considered in the design of rifle bolt actions to achieve a high degree of accuracy. One such factor of importance is the operation and construction of the firing pin assembly and means for cocking same. For example, it is important to reduce the firing pin travel as much as possible to achieve quicker ignition of the cartridge, and to minimize vibration and movement of the rifle from the time the trigger is pulled until the time the firing pin strikes the cartridge. Thus if the firing pin has a very long length of travel, wobble and vibration can cause reduction in the accuracy by the operator.

To achieve a short travel and still have sufficient force to ignite the cartridge, a large main spring is required for propelling the firing pin. However, it must be realized that the firing pin must be cocked against the compression of the large spring, thus requiring a greater force. Any additional stresses or torques exerted on the firing pin assembly when it is cocked causes binding of the firing pin and makes it harder to cock. In addition, lateral stresses or torques exerted on the firing pin cause greater wear and ultimate reduction in accuracy. Still further, torques and stresses cause the firing pin to wobble when released.

The present invention provides a cocking piece and cocking piece cover arrangement for being coupled to a firing pin assembly in a bolt action rifle, which permits the use of a large main spring for propelling the firing pin but which reduces to a minimum lateral stresses and torque exerted on the firing pin assembly when the firing assembly is cocked. The cocking piece is securely attached to the rear of the firing pin, with the firing pin being carried within the bolt. The cocking piece has a cam that rides on a cam surface in the rear of the bolt, so that the cocking piece and firing pin are forced rearward to cock the firing pin when the bolt is rotated. To achieve this, the cocking piece is constrained against rotation by the cocking piece cover within which it is housed. More particularly, the cocking piece cover rides on a rearward extension of the receiver so that it is prevented from rotating with the bolt. The cocking piece itself is contained between the cover and the receiver extension and bears against a combination of surfaces of the two so that it cannot be rotated. This combination of surfaces also prevents lateral stress and torque from being exerted on the firing pin when the cocking piece is forced rearward by the cam surface.

Many other objects, features and advantages of the invention will become readily apparent from the following detailed description thereof when taken in conjunction with the appended claims and the attached drawing wherein like reference numerals refer to like parts throughout the several figures, and in which:

FIG. 1 is a side elevational view, in section, of a rifle bolt action employing the cocking piece and cocking piece cover of the invention;

FIG. 2 is a fragmentary, bottom view of the rear portion of the bolt and the cocking piece, showing the relationship between the cam and the cam surface of the cocking piece and bolt, respectively, with the bolt in the forward but unlocked position;

FIG. 3 is a fragmentary, bottom view of the bolt and cocking piece and bolt in the forward but locked position, and the firing pin released to its forward, or striking position;

5 FIG. 4 is a schematic view of the rear of the bolt illustrating the angle of rotation of the bolt between the locked and unlocked positions;

FIG. 5 is a front elevational view, in section, of the locking system of the bolt action taken through section lines 5—5 of FIG. 1, showing the bolt in the forward but unlocked position;

10 FIG. 6 is a front elevational view, in section, of the locking system, showing the bolt in the forward but locked position;

15 FIG. 7 is a perspective view of the cocking piece;

FIG. 8 is a perspective view of the cocking piece cover with the cocking piece housed therein;

FIG. 9 is a bottom plan view of the cocking piece cover;

20 FIG. 10 is a side elevational view, in section, of the cocking piece and cocking piece cover; and

FIG. 11 is an end elevational view, in section, of the cocking piece and cocking piece cover, taken through section lines 11—11 of FIG. 10.

25 A composite view of the rifle bolt mechanism that employs the cocking piece and cocking piece cover of the invention is shown in the side elevational view, partly in section, of FIG. 1. The system includes a receiver 20 having a cylindrical bore or channel 22 extending longitudinally therein, and a cylindrical front portion 24 that is internally threaded along a length of the inner wall 26 for receiving and being secured to the threaded rear portion 28 of a barrel 30. The receiver includes a port 23 opening intermediate its ends in the top and along one side thereof through which cartridges may be loaded and unloaded. The barrel has a longitudinal bore 32 into which cartridges are chambered for firing.

30 A bolt 34 is carried within the cylindrical channel of the receiver for rotational and longitudinal movement therein. The bolt is rotated about a longitudinal axis as will be seen hereinafter for locking and unlocking the bolt within the receiver. The bolt is provided with longitudinal and centrally disposed cylindrical bore 36 of a first diameter and extending the major length thereof, another smaller diameter, cylindrical bore 38 located forward of the opening into the larger diameter bore 36, and a yet smaller diameter, cylindrical bore 40 located forward of and opening into bore 38. The smallest diameter bore 40 opens into a recessed front face 42 of the bolt, wherein the butt of the cartridge is seated within this recessed face when the cartridge is chambered for firing.

35 A firing pin assembly 44 is carried inside of the bolt and includes a cylindrical main body portion 45 having a forward portion 46 that rides within bore 38. An enlarged cylindrical shoulder 48 is disposed intermediate portions 45 and 46 against which a spring 50 abuts for urging the firing pin forward. The firing pin mechanism also includes an integral firing pin

lugs. The bolt includes a relatively short, reduced diameter section 58 immediately behind locking lugs 56, so that the maximum diameter across the front of the bolt locking lugs is equal to the major diameter of the bolt proper. Thus the bolt and locking lug system may be withdrawn longitudinally within the cylindrical bore of the receiver.

The main body portion 45 of the firing pin mechanism extends the length of the bore 36 of the bolt to approximately the rear face thereof, and includes a threaded extension 45' extending rearward thereof. A cocking piece 70 is threaded secured to the rearward extension 45' and serves to cock the firing pin mechanism for firing when the bolt is rotated, all as will be explained. The cocking piece is contained within a cocking piece cover 72, wherein the cocking piece cover is loosely threaded into the rear of the bolt. More particularly, a portion 76 of the inner wall of the bolt is threaded, and the cocking piece cover includes a forwardly extending threaded portion 78 that is loosely threaded into the rear of the bolt, so that the bolt may be rotated about a longitudinal axis relative to the cocking piece cover. The cocking piece cover rides on the receiver surface beneath it, which prevents the cover from rotating when the bolt is rotated. The cocking piece itself bears on inner surfaces of the cocking piece cover and on surfaces of the receiver to prevent it from rotation when the bolt is rotated, all as will be described in detail below.

A bolt handle 80 is secured to the bolt 34 at the rear portion thereof, and extends laterally from the side of the receiver immediately behind the rear edge 88 thereof. The rear edge of the receiver includes a beveled portion 89 adjacent the top thereof. The bolt may be rotated along a longitudinal axis by lifting the bolt handle 80, wherein the edge portion 89 engages the body 81 of the bolt handle during the last few degrees of rotation. When the bolt handle is raised to rotate the bolt, the bolt is unlocked by rotating the bolt locking lugs 56 to coincide with spaces between the receiver locking lugs 54, so that the bolt may then be retracted rearwardly in the receiver. On the last few degrees of rotation to unlock the bolt, the bolt handle body 81 engages edge 89 of the receiver to cause the bolt to be withdrawn a slight amount to break loose the cartridge within the chamber. As will be seen hereinafter, the construction of the locking lugs is such as to permit the slight rearward movement of the bolt over the last few degrees of rotation for unlocking it.

FIGS. 2-4 illustrate how the firing pin mechanism is cocked for firing when the bolt is rotated from the locked to the unlocked position. Both FIGS. 2 and 3 are fragmentary bottom views of the bolt and cocking piece, with FIG. 2 showing the cocking piece and firing pin mechanism in the cocked position with the bolt in the locked position, and FIG. 3 showing the firing pin and cocking piece in the fired position and the bolt in the locked position. As shown in FIG. 1 with the firing mechanism in the cocked position for firing, the cocking piece includes a portion 61 that has a front shoulder for being engaged by a sear 62 connected to the trigger mechanism. The sear holds the cocking piece and firing pin mechanism in a retracted, cocked position until the trigger 63 is pulled. The cocking piece also includes a cam 82 that rides along a corresponding cam surface 84 formed in the rear wall of the bolt 34. The cam surface is provided by cutting an arcuate section out of the

rear wall of the bolt, and the cam includes a rounded front face 83 for riding along this surface. As shown in FIG. 3, the cam is positioned at the bottom of the cam surface when the firing pin mechanism is in its most forward, fired position. As the bolt is rotated by lifting the bolt handle 80 upward, the cocking piece 70 and firing pin mechanism attached thereto are forced rearward relative to the bolt by action of the cam riding along the cam surface. Rotation of the cocking piece during this motion is prevented by the cocking piece cover, which has surfaces along which the cocking piece must ride to prevent any rotation.

The bolt is rotated until the cam 82 of the cocking piece completely clears the cam surface 84 provided in the rear of the bolt, as shown in FIG. 2. In this embodiment, the bolt is rotated an additional 5°, approximately, from where the center of the cam coincides with the beginning of the cam surface, as is schematically shown in FIG. 4, wherein it requires a rotation of approximately 45° between the positions of the cam as shown in FIG. 3 (fired position) and the position of the cam just as it clears the cam surface. The cam 82 is then resting in a slight indentation 85 in the rear wall of the bolt. The additional 5° of rotation is desirable so that the cam will be resting on a flat (or indentation 85) so that it will not slide back along the cam surface, when the bolt is longitudinally withdrawn rearward in the receiver to eject a spent cartridge.

As will be understood, the sear 62 is caused to extend upward in front of the shoulder 61 of the cocking piece when the cocking piece attains the position relative to the bolt as shown in FIG. 2. However, the sear cannot maintain the cocking piece and firing pin rearward when the bolt is withdrawn, and thus the necessity of the additional 5° of rotation to cock the firing pin. Then when the bolt is rotated in the opposite direction by urging the bolt handle downward so that the cam 82 is again in line with the bolt as shown in FIG. 3, but retracted relative thereto, the firing pin cannot be forced forward by the spring 50 until the trigger 63 is pulled.

Reference is not had to FIGS. 5 and 6, which are front elevational views, in section, showing the combination of the bolt and receiver locking lug system in the unlocked and locked positions, respectively. The receiver comprises four locking lugs 54 extending inwardly from the inner wall of the receiver with spaces 90 provided between adjacent locking lugs. Each of the receiver locking lugs has an arcuate length along the inner wall of the receiver that subtends an angle of 77°, and constitutes a segment of a circle, in cross-section, except for the forward chamfered surface thereof that will be discussed hereinafter. The minimum distance between the opposite locking lugs 54 is just slightly greater than the diameter of the reduced diameter bolt portion 58, so that the bolt may be withdrawn rearwardly in the receiver when it is unlocked.

There are four bolt locking lugs 56 that extend outwardly from the body of the bolt immediately forward of reduced diameter portion 58, each of which has two perpendicular edges 57 and 57' that terminate in a third, curved edges 91. Edge 91 generally conforms to the curvature of the receiver wall and is generally at an angle of 45° to edges 57 and 57'. The four bolt locking lugs form a substantially "square" configuration, except for the small curved edges 91. The spaces 90 between adjacent receiver locking lugs are slightly greater than the width of curved edge 91 of the bolt locking

lugs, so that the bolt locking lugs pass between the receiver locking lugs when the bolt is unlocked to withdraw it within the receiver.

Each receiver locking lug 54 has chamfered or beveled surfaces 63 and 64 cut into the forward face and inner side thereof, on either side respectively, of the center line of the lug. This allows the bolt to be moved forward over the first few degrees of rotation as it is rotated to the locked position. More specifically, the rear surfaces of the bolt locking lugs can be moved in front of the front edges of the receiver locking lugs where the latter are beveled, or chamfered, during the first few degrees of rotating the bolt shut when the body 81 of the bolt handle rides on beveled surface 89 of the receiver. An angle of rotation of approximately 40° to 55° is required to lock the bolt from the unlocked position, so that the bolt locking lugs are disposed in front of the receiver locking lugs as shown in FIG. 6.

A perspective view of the cocking piece 70 is shown in FIG. 7 and comprises a forwardly extending lower cam 82 having a curved face 83 thereon. Another forwardly extending member 110 is spaced above cam 82 with a threaded bore 111 extending longitudinally between members 82 and 110 and completely through the cocking piece. Another member 114 extends upward from the main body of the cocking piece immediately rearward of member 110 and forms a shoulder 112 therewith. A pair of opposite member 115 and 116 extend laterally on either side of the cocking piece and having horizontal, plane shoulders 117 and 118 at the top thereof and beveled shoulders 119 and 120 at the bottom thereof, respectively. Horizontal shoulders 117 and 118 are spaced below the top horizontal surface of member 114. Another member or tongue 61 extends downwardly and along the bottom of the cocking piece from immediately behind cam 82 and rearward of members 114, 115 and 116. Member 61 also extends below the bottom of cam 82 and includes a slightly beveled lower front edge 125 immediately below cam 82 where it joins the main body of the cocking piece. Surface 125 is engaged by the sear of the trigger mechanism to prevent firing or forward movement of the firing pin assembly until the trigger is pulled, all as will be explained hereinafter. Member 61 includes part 128 extending rearward of members 114, 115, and 116, and which forms a lateral slot 130 with these members. Although not pertinent to the invention, slot 130 cooperates with a safety piece 131 (shown in FIG. 1) to lock the cocking piece in a rearward position.

Reference is now had to FIGS. 7-11 to describe the cocking piece and cocking piece cover arrangement. FIG. 8 is a perspective view of the cocking piece cover showing the cocking piece contained therein. FIG. 9 is a bottom view of the cocking piece cover and cocking piece with the bolt attached, the latter being fragmentarily shown. FIG. 10 is a side elevational view, in section, of the bolt, receiver, cocking piece and cocking piece cover with the section being taken through the longitudinal center plane of the bolt action rifle. And, FIG. 11 is a rear elevational view, partly in section, taken through section lines 11-11 of FIG. 10, also showing the cocking piece in phantom.

The cocking piece cover 72 includes a main body portion 140 having a pair of spaced apart, flat horizontal surfaces 141 and 142 at the bottom and on opposite sides thereof (See FIGS. 9 and 11). A main cavity 150 is provided within the interior of the cocking piece

cover between flat sides 141 and 142 and which opens through the bottom thereof. This main cavity accommodates the main body portion of the cocking piece 70. A slot 153 extends upwardly into the body of the cocking piece cover from cavity 150, so that cavity 150 defines plane surfaces or shoulders 151 and 152 on opposite sides of slot 153. Slot 153 has a flat roof 154 and opposing side walls 155 and 156 perpendicular thereto (see FIG. 11). The cover is provided with a recessed front wall 159 forming one end of cavity 150, and which has a vertical slot 160 extending through the center thereof and opening through the bottom of the cover. The recessed front wall 159 is positioned rearward of the front face 143 of the cocking piece cover, so that a partially annular space 144 is provided in the front face of the cocking piece cover. Threaded extension 78 of the cocking piece cover extends forwardly of the front face 143 for being loosely threaded into the interior of bolt 34. The threaded extension 78 is a part of a cylindrical shank portion 78' that extends from the front wall 159, wherein a vertical slot 161 is cut in the shank portion as a continuation of slot 160 for accommodating cam 82 of the cocking piece. Bolt 34 accordingly extends into the annular recess 144 adjacent front wall 159.

The cocking piece cover also includes an interior wall 165 having a vertically extending slot 166 therein, and forms the rear of cavity 150. Another cavity 164 is provided in the cocking piece cover between interior wall 165 and a rear wall 169 of the cocking piece cover.

To assemble the apparatus, the cocking piece 70 is inserted in the cocking piece cover from the bottom thereof, with this being possible because of cavities 150 and 164, and slots 160, 161 and 166 opening into the bottom of the cocking piece cover. With the cocking piece positioned within the cover in this manner, the threaded rearward extension 45' of the firing pin is inserted through the central bore 79 in the threaded extension 78 of the cocking piece cover, so that spring 50 is contained between shoulder 48 of the firing pin and the front surface of threaded extension 78. The firing pin is then securely screwed into the cocking piece within threaded bore 111 therein. Because of the compression of the spring, the cocking piece is now in a forward position with cam 82 passing through slot 160 extending into slot 161, bearing against the front wall thereof. The bolt itself is now threaded onto the threaded extension 78. To do this, spring 50 is further compressed so that the cocking piece is held in the rearward position relative to the cocking piece cover. The bolt is then loosely threaded over forward threaded extension 78 until the back wall thereof is adjacent the front surface of front wall 159, and the arcuate cam surface 84 coincides in a vertical plane with cam 82. The cocking piece is then released so that cam 82 moves forward into the cam surface of the bolt, all as is shown in FIG. 9. Since the bolt can be rotated relative to the cocking piece cover, cam 82 is urged rearward as the bolt is rotated.

Referring more particularly to FIGS. 10 and 11, the combination of the bolt, firing pin, cocking piece and cocking piece cover is shown assembled into the channel of the receiver, wherein the receiver includes a rearwardly extending tang 172 that defines a curved surface 173 opening in the top thereof and an elongated rectangular slot 174 extending horizontally therein and opening into the curved surface 173. The

tang also includes opposite flat horizontal surface 175 and 176 on which flat surfaces 141 and 142 of the cocking piece cover ride, respectively. The bottom arcuate edges of front and intermediate walls 159 and 165 extend below flat surfaces 141 and 142 and ride on the curved surface 173 of the tang, whereas bottom member 61 of the cocking piece rides within slot 174.

Rotation of the bolt so that the cocking piece is forced rearward as cam 82 rides on surface 84 tends to cause the cocking piece to undergo all of "pitch," "yaw" and "roll," and to exert a torque on the firing pin shaft. However, the cocking piece and firing pin assembly are relieved of substantially all stresses and torque as they are forced rearward when the bolt is rotated relative to the cocking piece cover. Specifically, the cocking piece is prevented from undergoing "pitch" which would cause a vertical stress or torque on the firing pin shaft, since the cocking piece is vertically constrained between horizontal surfaces 151, 152 and 154 on the one hand and horizontal surface 174 on the other hand. The cocking piece is also prevented from undergoing "yaw" which would cause a horizontal stress or torque on the firing pin shaft, since the cocking piece is horizontally constrained between the vertical surfaces of slots 153, 160, 166 and 174. Finally, the cocking piece is prevented from undergoing "roll" which would cause it and the firing pin shaft to rotate with the bolt, since the cocking piece is constrained against rotation between all of the aforementioned surfaces.

Although the invention has been described with reference to a particular embodiment thereof, certain modifications and substitutions that do not depart from the true scope thereof will undoubtedly occur to those skilled in the art. Accordingly, it is intended that the invention be limited only as defined in the appended claims.

What is claimed is:

1. In a bolt action rifle including a receiver having a bolt channel therein, a bolt rotatably and slidably carried in said bolt channel and adapted to be locked against sliding movement in said receiver when rotated to a locked position, firing pin mechanism carried in said bolt, a cocking piece attached to said firing pin mechanism having a cam for cooperating with a cam surface on the rear of said bolt for being forced rearward to cock said firing pin mechanism when said bolt is rotated relative thereto, a cocking piece cover housing said cocking piece and preventing said cocking piece from rotating when said bolt is rotated, said receiver having a rearward extending tang along which said cocking piece and cocking piece cover ride, the improvement comprising:

- a. said cocking piece cover comprises a main cavity opening through the bottom thereof within which said cocking piece is contained, said cavity including front and rear vertical walls having slots extending vertically therein,
- b. said cocking piece includes forward and rearward members extending through the slots in said front and rear walls, respectively, of the said cocking piece cover, so that said cocking piece is constrained from rotational movement about a first axis when said cocking piece is forced rearward to cock said firing pin mechanism, and
- c. said cocking piece cover, said cocking piece and said receiver tang having cooperating surfaces constraining said cocking piece from rotational movement about a second axis perpendicular to said first axis when said cocking piece is forced rearward to cock said firing pin mechanism.

2. In a bolt action rifle as set forth in claim 1 wherein said cavity of said cocking piece cover has a first channel opening in the top thereof extending longitudinally therealong and having a roof, said receiver tang includes a second channel opening in the top thereof extending longitudinally therealong, and having a floor therein, said cocking piece includes an upper member extending into said first channel having an upper surface for engaging said roof, a lower member extending into said second channel having a lower surface for engaging said floor, and said cooperating surfaces comprises the combination of said roof and said floor, and said upper and said lower surfaces of said cocking piece.

3. In a bolt rifle as set forth in claim 2 wherein said first channel has opposing vertical walls, and said upper member of said cocking piece includes vertical sides that engage said opposing vertical walls, respectively.

4. In a bolt action rifle as set forth in claim 1 wherein said cocking piece cover includes a threaded member extending forwardly of said front vertical wall for being threaded into the rear of said bolt, in which said slot extending vertically in said front vertical wall continues into said threaded member.

5. In a bolt rifle as set forth in claim 2 wherein said second channel has opposing vertical walls, and said lower member of said cocking piece includes vertical sides that engage said opposing vertical walls, respectively.

6. In a bolt action rifle as set forth in claim 1 wherein said forward member of said cocking piece comprises a cam having a rounded front surface for riding on said cam surface in said bolt.
